United States Patent [19]
Graybill

[11] Des. 259,159

[45]  May 12, 1981

[54] LETTER HOLDER

[76] Inventor: John Graybill, Lot #9, Rte. 2
Columbia, Dover, Ohio 44622

[] Term: 14 Years

[21] Appl. No.: 952,623

[22] Filed: Oct. 19, 1978

[51] Int. Cl. .... D6—04

[52] U.S. Cl. D6/114; D6/130

[58] Field of Search D6/114, 130, 157, 134;
211/10, 13, 50, 55, 87, 88, 90, 106

[56] References Cited

U.S. PATENT DOCUMENTS

D. 249,913 10/1978 Nicely D6/134

301,204	7/1884	Berry	211/50
518,252	4/1894	Keller	211/106
575,590	1/1897	Brightman	211/50
941,653	11/1909	Rothengatter	211/106
959,839	5/1910	Buehler	211/50

Primary Examiner—B. J. Bullock

Attorney, Agent, or Firm—Hamilton, Renner & Kenner

[57] CLAIM

The ornamental design for a letter holder, as shown and described.

DESCRIPTION

FIG. 1 is a front elevational view of a letter holder embodying my new design;

FIG. 2 is a side elevational view thereof;

FIG. 3 is a rear elevational view thereof;

FIG. 4 is a bottom plan view thereof.

U.S. Patent

May 12, 1981

Des. 259,159

FIG. 1

FIG. 2

FIG. 3

FIG. 4